United States Patent Office

Des. 195,100
Patented Apr. 23, 1963

195,100

OPTICAL COMPARATOR GAUGE

Frank M. Flynn, Binghamton, N.Y., assignor to General Aniline & Film Corporation, New York, N.Y., a corporation of Delaware

Filed Aug. 3, 1961, Ser. No. 66,189

Term of patent 14 years

(Cl. D57—1)

FIG.1

Des. 195,100

PAGE 2

FIG.2

FIG.3

FIG. 1 is a perspective view taken from one side of an optical comparator gauge showing my new design; FIG. 2 is an elevational view taken from the other side thereof;

FIG. 3 is a front elevational view thereof.
I claim:

The ornamental design for an optical comparator gauge, substantially as shown.
